US0D1068565S

(12) **United States Design Patent** (10) **Patent No.:** **US D1,068,565 S**
(45) **Date of Patent:** **** Apr. 1, 2025**

(54) **FRAME FOR CYCLES AND MOTORCYCLES**

(71) Applicant: **EXGINEERING SA**, Manno (CH)

(72) Inventors: **Federico Bordoni**, Manno (CH);
Simone Maccagnan, Manno (CH);
Francisco Martins Carabetta, Manno
(CH); **Pierpaolo Ruttico**, Manno (CH);
Salvatore Urso, Manno (CH)

(73) Assignee: **EXGINEERING SA**, Manno (CH)

(**) Term: **15 Years**

(21) Appl. No.: **29/875,465**

(22) Filed: **May 5, 2023**

(30) **Foreign Application Priority Data**

Nov. 9, 2022 (EM) 015002682

(57) **CLAIM**

The ornamental design for a frame for cycles or motorcycles, as shown and described.

DESCRIPTION

FIG. 1 is a top, right side perspective view of the frame for cycles or motorcycles;

FIG. 2 is a right side elevation view thereof;

FIG. 3 is a top plan view thereof;

FIG. 4 is a front elevation view thereof;

FIG. 5 is a rear elevation view thereof;

FIG. 6 is a rear and right side perspective view thereof; and, FIG. 7 is a rear and left side perspective view thereof.

1 Claim, 7 Drawing Sheets
